[57] CLAIM

The ornamental design for a massager, as shown and
described.

DESCRIPTION

FIG. 1 is a perspective view of a massager, showing my
new design;

FIG. 2 is a top plan view thereof;

FIG. 3 is a front elevational view thereof, the rear elevational
view being identical thereto;

FIG. 4 is a left side elevational view thereof, the right side
elevational view being identical thereto; and,

FIG. 5 is a bottom plan view thereof.
